UNITED STATES PATENT OFFICE.

JAMES G. HILL, OF WASHINGTON, DISTRICT OF COLUMBIA.

SLATE-FASTENER.

SPECIFICATION forming part of Letters Patent No. 241,983, dated May 24, 1881.

Application filed April 12, 1881. (No model.)

To all whom it may concern:

Be it known that I, JAMES G. HILL, of Washington, in the District of Columbia, have invented a new and useful Improvement in 5 Slate-Fasteners, of which the following is a clear, full, and exact description, reference being had to the accompanying drawings, making a part of this specification, in which—

Figure 1 shows my improved method of fastening slate to T-iron purlins. Fig. 2 is a modification of the same, adapting the fastenings to angle-iron purlins. Fig. 3 shows another modification of my invention when made of wire. Fig. 4 is a side view of the purlin with 15 the fastening applied thereto. Fig. 5 is a view of the wedge.

To enable others skilled in the art to make and use my invention, I will proceed to describe the exact manner in which I have carried it out.

My invention has reference to securing roofing-slate in position; and it consists in the combination of devices hereinafter described and claimed.

25 In the drawings, A represents a T-iron purlin, and a a' a'' slates secured in position.

B represents a piece of strap-iron bent into the shape as shown, the end b passing through a slot made in the side of slate a', and bent at 30 a right angle down upon the surface of the slate. The other end of the strap is bent at a right angle in the opposite direction, and of sufficient length to press firmly against the purlin, as shown in Fig. 1, and thus to steady 35 the strap. Near the lower bend of the strap

I make the slot C to receive the metal wedge D, which is tapering and of sufficient length to be adapted, when driven home, to be turned or clinched over the opposite edge of the purlin.

If wire be used instead of strap-iron, it is to 40 be bent in the form E, (shown in Fig. 3,) and the bottom loop in the wire serves for the slot through which to drive the wedge. I prefer, however, to use the strap-iron as being better adapted for the work.

When angle-iron purlins are used, as shown 45 in Fig. 2, it is evident that the lower end of the strap may be bent around the edge F of the iron and the wedge for tightening introduced between the iron and the bent strap 50 without departing from the spirit of my invention.

I am aware that strap-iron has been used for fastening slates to the purlins; but with them have been used screw-threaded bolts 55 with nuts, and these bolts have their heads countersunk in the slate, rendering the fastening costly. The object of my present invention is to simplify and cheapen the article.

Having thus described my invention, what 60 I claim as new, and desire to secure by Letters Patent, is—

The iron strap B, bent as described, and provided with the slot C, in combination with the wedge D, substantially as and for the purpose set forth.

JAS. G. HILL.
